UNITED STATES PATENT OFFICE.

CHARLES W. HAWTHORNE, OF HAMILTON, ONTARIO, CANADA, ASSIGNOR TO MORGAN CONSTRUCTION COMPANY, OF WORCESTER, MASSACHUSETTS, A CORPORATION OF MASSACHUSETTS.

ROLLING-MILL.

1,302,921.

Specification of Letters Patent.

Patented May 6, 1919.

Application filed March 16, 1916. Serial No. 34,579.

To all whom it may concern:

Be it known that I, CHARLES W. HAWTHORNE, a citizen of the United States, and a resident of Hamilton, Ontario, Canada, 5 have invented certain new and useful Improvements in Rolling-Mills, of which the following is a specification.

The invention relates to guides for rolling mills, and more particularly to a guide 10 adapted to receive and take the lead end of a rod or bar irrespective of deflections or variations in position thereof in approaching the guide, and coaxing with the roll pass to center the rod or bar on the axis of 15 the roll pass. The objects and advantages of the invention will be set forth herein-after in part and in part will be obvious herefrom, such advantages and objects being attained by the mechanisms and instru- 20 mentalities set out in the accompanying claims.

The invention consists in the novel parts, constructions, combinations and improvements herein shown and described.

25 The accompanying drawings, herein referred to, and constituting a part hereof, illustrate one embodiment of the invention, and together with the description serve to explain the principles thereof.

30 Of the drawings:

Figure 1 is a side elevation of a stand of rolls with its housing, and showing the guide in vertical longitudinal cross section;

Fig. 2 is a detail plan view of an embodiment of the guide, on an enlarged scale;

Fig. 3 is a section on the line 3-3 of Fig. 2;

Fig. 4 is a section on the line 4-4 of Fig. 2;

40 Fig. 5 is a detail, in elevation, of one of the halves of the guide;

Fig. 6 is a perspective view of the guide holder;

Fig. 7 is a perspective view of the holder- 45 box;

Fig. 8 is a detail plan, of larger size, of an embodiment utilizing a clamping and releasing wedge for the guide;

Fig. 9 is a vertical section of Fig. 8 just 50 within the top of the guide holder, parallel to the plane of the paper; and

Fig. 10 is an elevation looking at Fig. 8 from the bottom.

Referring by way of example to the illus- 55 trated embodiment, a stand of rolls is shown

in a general way, but with much of the detail omitted. The bed-plate is indicated by 1, with the housing 2 resting thereon or integral therewith, and the cap-plate 9 resting upon the housing. The lower roll 3 is journaled in bearing blocks 4 carried by the 60 housings, and the upper roll 5 is journaled in bearing blocks 6 working in guides in the housings 2, and adjustably held in position by suitable means, indicated generally by 65 reference numeral 7. The guide is shown in position to direct the rod or bar to be rolled into the roll pass.

One great difficulty with present guides is a failure to take or receive the forward end 70 of the rod or bar despite variations and deflections in its position, and at the same time to guide the rod or bar fairly and truly through the pass. The guide of my present invention is laterally or horizontally ad- 75 justable or positionable on the rest bar, and in connection therewith the guide, and preferably the holder therewith, are swiveled horizontally on the holder box, that is, so that the guide while held bodily is free to 80 move angularly horizontally. An advantage of this angular or swivel movement is to prevent undue wear on the guide, and also upon the roll pass, for if the guide be off center, the wear is thereby thrown on 85 one side of the roll pass, the rolls and the guides wearing most at the place where the pressure is greatest.

The guide of the present invention will center itself on the roll pass the moment 90 the front end of the bar or rod enters the pass. By this invention a great deal of time is saved in the resetting of the rolls and guides, due to the fact that the guide does not have to be alined so accurately to pass in 95 adjusting the rolls and guides, and by reason of the guide being self-centering, due to the swiveled or movable mounting, the bar or rod going fairly and truly through the pass. In addition to the advantages already 100 pointed out, it avoids or obviates any deformation of the cross section, and the formation of minute fins or cross sectional malformations extending along the rod.

Referring to the construction as shown in 105 Figs. 1 to 7 of the drawings, a rest bar 8 extends across from one housing to the other. The guide holder box 10 rests upon the bar 8, the upper surface of the rest bar 8 having a guideway 11 formed therein and 110

the holder box having a downwardly projecting guide portion 12 adapted to rest in the guideway 11 while the other parts 13 of the bottom of the holder box 10 rest upon 5 the upper face of the rest bar 8. The holder box is positionable or adjustable along the rest bar, and is held in position by suitable means, such as a bolt 14, the head thereof resting in a recess 15 in the holder box 10, 10 the bolt passing through a suitable slot in the rest bar 8.

The holder box comprises a bottom 16 and side walls 17 and 18, the upper portion or top being preferably open except at the forward end thereof, the side walls preferably flaring or inclining outwardly toward the rear (see especially Figs. 2 and 4), the interior of the box being of increasingly greater width from the front toward the rear. The bottom of the holder box is preferably cut away as shown at 20, Figs. 3, 4 and 7, to decrease the wearing and frictional surface. At its forward end the holder box is provided with a top or cross piece 21.

25 Within the holder box is positioned and supported the guide holder 26. The guide holder 26 is shown with a flange or outwardly extending portion 27 at its forward end and with its walls 28, 29, 30 and 31, extending backwardly therefrom. The side walls 29 and 31 terminate rearwardly in arcuate or rounded projections 32 and 33 shaped to fit between the rolls and to extend at their center inwardly to, or closely adjacent to, the roll pass.

Means are provided for permitting an angular motion of the guide holder in the holder box in a horizontal direction, and in the embodied form of such means the flange 40 27 is provided centrally at the top and bottom thereof with arcuate lugs 34 and 35, the arcuate lugs resting against the front face of the holder box (see especially Figs. 1, 2 and 3). The guide holder is of a size to practically fill the front end of the opening or interior of the holder box, but by reason of the guide holder being preferably of uniform size throughout its length and the holder box increasing in size toward the rear, 45 the guide holder will rock horizontally upon the bearings 34 and 35, while the close fit at the forward end holds the guide holder in alinement for the adjusted position of the holder box.

50 55 The guide proper comprises two separate or separable halves considered longitudinally thereof (Figs. 1, 3, 4 and 5). The halves of the guide together comprise a flaring or bell-shaped mouth 40 to receive the forward end 60 of the rod or bar. To the rear of these is a flange or collar 41, which collar rests against the forward end of the guide holder. The main body 42 of the guides extending backwardly from the flange 41, fits snugly within 65 the guide holder 26 (see Figs. 1, 3 and 4), so

that the guide and guide holder move together. The interior orifice or passageway 43 formed by the guide holders decreases in size to the inner end, to guide the forward end of the bar or rod fairly and truly into 70 the pass. The inner end 44 of each half of the guide is arcuate shaped, conformably to the inner end of the guide holder, to fit between the rolls and to lead up closely to the roll pass.

75 On the finishing pass, and sometimes in other cases, it is frequently necessary to work within close dimensions. For such work it is provided by my invention that the guide holder retains its centering and truing 80 functions as above described, and also that the guide itself can be opened, or is permitted to be open, until the rod has entered the pass and the centering or truing action has occurred, when the guide is closed up and 85 held firmly in the trued position.

As embodied, in Figs. 8, 9 and 10, the guide holder 50 is shown, with the various parts thereof indicated by the reference numerals heretofore used. The guide lies 90 loosely therein (omitted from the figures for sake of clearness) and alongside the guide is a sliding wedge 51. Wedge 51 has a notch 52 therein in line with a slot 53 in guide holder 50. A rod 54 has a bent end 55 extending through slot 53 and engages in the notch 52. Rod 54 at the other end has a yoke 56 engaging a pin 57, which pin is on one arm of a lever 58. Lever 58 is pivoted on a suitable bearing such as a bracket 59 on the 100 roll stand housing. After the leading end of the rod has entered the pass while the guide is open or loose and the truing action has taken place, the attendant throws lever 58 and the guide is then firmly held in the 105 trued position while the rod is run through the pass. It will be understood from all the foregoing that the roll pass will center and aline the guide relatively to the pass. The 110 rolling action on the bar or rod entering the rolls brings the guide and the bar or rod in alinement with the true line of the roll pass.

115 From all the foregoing it is seen that a construction has been provided realizing the objects and advantages herein set out, together with other objects and advantages which will be obvious to those skilled in the art. It will be understood that changes may be made from the precise structures shown and described within the scope of the appended claims and without sacrificing the chief advantages of the invention.

120 What I claim as my invention and desire to secure by Letters Patent is:—

1. The combination with the rolls and roll 125 pass of a guide support, and an inclosing guide for the metal entering the roll pass, said inclosing guide having angular movement relatively to the guide support.
2. The combination with the rolls and roll 130

pass of a rest bar, a guide support positionable along the rest bar and a guide for the roll pass, said guide being horizontally angularly movable on said guide support during the passage of the metal therethrough.

3. The combination with the rolls and roll pass of a guide support, and a guide for the roll pass having angular movement relatively to the guide support about a point

10 near the entering end of said guide.

4. The combination with the rolls and roll pass of a rest bar, a guide support positionable along the rest bar and a guide for the roll pass, said guide being horizontally angularly movable on said guide support during the passage of the metal therethrough about a point near the entering end of said guide.

5. The combination with the rolls and roll pass of a rest bar, a guide support positionable along the rest bar and a guide for the roll pass, and a rocking vertically disposed bearing between the guide and its support at the center of the entering end of the guide.

20 6. A guiding device for a roll pass including in combination an interiorly apertured guide, an interiorly apertured support for the guide, said support inclosing the guide closely at the forward end and loosely at 25 its rear end, and a vertically disposed rocking bearing between the guide and its support at the center of its entering end.

7. The combination with the rolls and roll pass of a rest bar, a holder box positionable 30 along the rest bar, a guide holder adapted to rock horizontally relatively to the holder box, and a removable guide carried by the guide holder.

8. The combination with the rolls and roll 35 pass of a rest bar, a holder box positionable along the rest bar, a guide holder adapted to rock horizontally relatively to the holder box, and a multi-part guide carried by the guide holder.

40 45 9. The combination with the rolls and roll pass of a rest bar, a holder box positionable along the rest bar, a guide holder removably held within the holder box, said guide holder

being adapted to rock horizontally relatively to the holder box, and a removable guide carried by the guide holder.

10. The combination with the rolls and roll pass of a rest bar, a holder box positionable along the rest bar, a guide holder removably held within the holder box, said guide holder being adapted to rock horizontally relatively to the holder box, and a multi-part removable guide carried by the guide holder.

11. The combination with the rolls and roll pass of a holder box, a guide holder adapted to rock horizontally relatively to the holder box, a guide loosely disposed within said guide holder, and means for closing the guide.

12. The combination with the rolls and roll pass of a holder box, a guide holder adapted to rock horizontally relatively to the holder box, a guide loosely disposed within said guide holder, and a wedge within the guide holder movable to cause the closing of the guide.

13. The combination with the rolls and roll pass of a holder box, a guide holder adapted to rock horizontally relatively to the holder box, a guide loosely disposed within said guide holder, a wedge within the guide holder movable to cause the closing of the guide and means for moving the wedge.

14. The combination with the rolls and roll pass of a holder box, a guide holder adapted to rock horizontally relatively to the holder box, a guide loosely disposed within said guide holder, a wedge within the guide holder movable to cause the closing of the guide and means for moving the wedge including a member movable by the operator after the forward end of the rod has passed through the guide and entered the roll pass.

In testimony whereof, I have signed my name to this specification, in the presence of two subscribing witnesses.

CHARLES W. HAWTHORNE.
